UNITED STATES PATENT OFFICE

PATRICK FOY, OF CHICAGO, ILLINOIS

ELECTRIC SIGNAL LAMP

Application filed August 26, 1927. Serial No. 215,661.

This invention relates to an electric signal lamp and has for an object to provide an improved mounting for the electric light bulbs of simplified and durable construction, which 5 may be economically manufactured. A special object of the improved mounting is to obviate possible injury to the bulbs due to insertion and extraction from the sockets. A further object is to provide simplified electrical connections to signal lamps, especially 10 those having two separate signals, such as in the combination stop and tail lights used on automobiles. It consists in certain features and elements of construction, herein shown 15 and described as indicated by the claim.

In the drawings:

Figure 1 is a plan view of a combination stop and tail light signal lamp with the cover removed, illustrating the improved bulb 20 mounting.

Figure 2 is a plan view of the casing of the signal lamp shown in Figure 1, with bulbs and mounting removed to show the electrical contact connections.

25 Figure 3 is a perspective view of the improved mounting, illustrating the manner of supporting the bulbs.

Figure 4 is a longitudinal section through the complete signal lamp taken substantially 30 as indicated by line 4—4, Figure 1.

Figure 5 is a transverse section through the casing, taken on line 5—5, Figure 2, showing the socket for the lead in terminals and electrical connections for the bulbs.

35 The signal lamp, as illustrated in the drawing, is of the combination stop and tail light type, having a pressed metal casing, 10, and a cover, 11. The cover which is fitted with glasses, 12, for alignment over the respective 40 compartments of the casing, is attached thereto by screws, 13, engaging lugs, 14, formed on the inner wall of said casing. The casing is divided into two compartments, 15, and 16, by a partition plate, 17, slidable transversely 45 in the casing between a pair of guide strips, 18, secured to the inner walls of the casing, on opposite sides.

The upper edge of the partition plate engages the underside of the cover so as to substantially exclude the light from one com-

partment to the other. These compartments, 15 and 16, serve respectively as stop light and tail light compartments and are provided with electric light bulbs, 19 and 20, mounted in a removable carrier, of which the partition 55 plate, 17, is a main part. The bulbs are of the usual single contact type, with the center contact point 21 at the bottom of the metal base, 22. The bulb, 19, is considerably larger than bulb, 20, in the tail light compartment, 60 due to the fact that greater intensity of light is required in daylight to make the stop light signal plainly visible. The removable carrier includes a bracket, 23, attached to the partition plate, 17, and extending into the 65 tail light compartment and having its end portion, 24, bent at a right angle and parallel to said partition plate. The partition plate is cut adjacent the center to form a pair of laterally extending supporting lips, 25, for 70 the base of the bulb, 19, while the end portion, 24, of the bracket is also provided with lip supports, 26, for the base of the small bulb, 20. As may be seen from the drawing these 75 lip supports extend toward the opposite ends of the casing for supporting the respective bulbs in opposite relation, but in central alignment with the casing and each other. On both the partition plate and end portion, 24, of the bracket are additional pairs of supporting 80 lips, 27, formed intermediate the lips, 25, and 26, and extending laterally in opposite direction to the lips, 25 and 26. The lips, 27, of each pair are disposed diametrically opposite each other and are each provided with a usual irregular slot, 28, for engagement by the studs, 30, on the bases of the bulbs for the 85 usual bayonet socket connection. The lips, 25, 26 and 27 are all shaped to conform to the curved bases of the respective bulbs which 90 they support.

As may be seen from Figure 4 the contact points, 21, of the bulbs, extend beyond the lips, 27, the contact on bulb, 19, being engaged 95 by a spring contact bar, 31, carried on an insulating block, 32, and extending therethrough with the end terminating in a contact point within the lead in wire socket, 33, which is secured as by soldering to the outside 100 of the bottom or back of the casing, 10, hav-

ing prongs, 34, extending upwardly through the insulating block, 32, and clinched thereover for holding the same in place. A second spring contact bar, 35, engages the contact, 21, on bulb, 20, and is also secured to the insulated block with its end terminating in a contact point in socket, 33.

Thus it will be clear that the spring contact bars, 31 and 35, will yieldingly maintain the bulbs, 19 and 20, in locked position in their sockets formed by the lips, 25, 26 and 27. Further, the bulbs are held in position and cannot without extremely excessive jarring become dislodged from their sockets. Yet, the carrier, which comprises partition plate, 17, and bracket, 24, may be bodily removed from the casing at will, together with the bulbs, 19 and 20, by merely removing the cover 11; the contact bars, 31 and 35 being slidably disengageable from the contacts on the bulbs. After extracting the carrier from the casing, the bulbs, being released from pressure of the contact springs, 31 and 35, may be easily removed from their sockets. This arrangement avoids breaking and damaging the bulbs in removing or inserting in sockets, which heretofore frequently resulted, due to either corrosion of the bulb base to the socket or to excessive spring pressure at the contact, causing breakage when compressing the spring while turning the bulb in the socket.

It will be understood that the bulbs, 19 and 20 for the stop and tail lights respectively are operated independently; the base of bulb 19 being grounded through partition plate, 17, thence through the casing and the vehicle frame, and contact, 21, of said bulb, 19, completing the circuit through contact bar, 31, the terminal of which is connected by suitable lead-in wire to a switch (not shown) on the brake or clutch as the case may be. The tail light bulb, 20, through its base is grounded through bracket, 24, and partition plate, 17, to the vehicle frame; the contact bar, 35, completing the circuit through suitable lead-in wire to the terminal of said bar to a switch on the vehicle in a usual manner. The electrical connections need not be further explained, except to point out that the connection to a combination fixture, as herein described, is simplified by having only one socket to the casing, for lead-in wires for operating both signals.

A pair of studs, 40, are riveted to the bottom of the casing, 10, for mounting the signal device on a vehicle. The tail light compartment, 16, has an opening, 41, cut into the end portion of the wall of the casing, which is the bottom of the casing when the device is in mounted position. This opening may be covered by a screen or piece of suitable transparent material, such as celluloid, as indicated at 42, so that the light from the tail light, 20, may be also directed downward in a customary manner.

I claim:

A signalling apparatus comprising a casing having a back wall and an open front face, a pair of stationary contact fingers carried by the back wall, a bulb carrier for the casing, said carrier being removable from and insertable into the casing through the open front wall thereof, lamp bulbs mounted on the carrier with their base contacts engaging the stationary contact fingers when the carrier is in place within the casing, the stationary contact fingers being directed forwardly in the general direction of movement of the base contacts of the bulbs whereby to prevent interference between the contact fingers and the bulb carrier, and a cover plate for the open front end of the casing, said cover being removable independently of the carrier for inspection of the bulbs, contact fingers, and carrier positioned within the casing.

In testimony whereof I have hereunto set my hand at Chicago this 24th day of August, 1927.

PATRICK FOY.
